UNITED STATES PATENT OFFICE.

CHARLES KENISTON, OF BOSTON, MASSACHUSETTS.

HAND-PRESS FOR PRINTING.

Specification of Letters Patent No. 12,553, dated March 20, 1855.

To all whom it may concern:

Be it known that I, CHARLES KENISTON, of Boston, county of Suffolk, the State of Massachusetts, have invented a new and useful Improvement in Printing-Presses; and I do hereby declare the following is a full and exact description thereof, reference being had to the accompanying drawing, and to the letters of reference marked thereon.

10 The advantage my press has over others now in use, for the same purpose, it being so constructed there is an extended arm on which a piston and type are attached the same operating upon a swivel, the whole being attached to a solid bed. There are two pads attached to said bed, one for the purpose of inking the type, the other for the article to be placed when printing. The operator by turning said arm over the pads, 15 and striking a light blow upon the top of the piston alternately, will ink, and print, with the accuracy that no other press has done. Another advantage in its favor, the operator, can at pleasure, make an impression upon any part of the article he chooses. In this process there is no blurring of the article printed upon. After giving an impression the operator has both hands at liberty to prepare articles for further operation.

20 To enable others skilled in the art to make and use my invention, I proceed to describe its construction and operation.

Figure 1, is a plan of the entire machine

or press. Fig. 2, is a section elevation is 35 cut and corresponding with the line in plan Fig. 1, X, X. Fig. 3 is a plan which corresponds with the part of Fig. 1, marked g, e, Fig. 4, is a plan represents an arm on a line of X, X, of Fig. 1, and covers Fig. 3. 40

The letter A, is the handle of piston B, there being attached at its end a die marked G, the whole having a reciprocating motion through the arm D.

The letter C, is a spiral spring is attached or surrounds the piston B, for the purpose of giving the die an open position.

The letter D, is an extended arm which has an oscillating motion and turns upon the bed F, F. The bed F, F, is intended to 50 hold the pads H, H, also supports the arm D.

The letter h, is a pin for the purpose of keeping the pads in their proper places. The set screw a, operates in slot b, gives the 55 piston a steady and direct motion. The set screw g, holds firmer the die in its socket.

The letter d, represents a check pin, and the catch e, allows the arm D, to oscillate at a given distance.

60 What I claim as new and desire to secure by Letters Patent is—

The arrangement and construction of the press as herein described.

CHARLES KENISTON.
